(57) **CLAIM**

(21) Appl. No.: **29/344,729**

The ornamental design for a navigation device mount for use
on a handgrip of a vehicle, as shown and described.

(22) Filed: **Oct. 2, 2009**

DESCRIPTION

(51) **LOC (9) Cl.** **08-05**

FIG. 1 is a perspective view of a navigation device mount for
use on a handgrip of a vehicle showing our new design;

(52) **U.S. Cl.** **D8/349**

FIG. 2 is a right side view thereof;

(58) **Field of Classification Search** D8/349,

FIG. 3 is a left side view thereof;

D8/354, 300, 303, 306, 310, 107, DIG. 9—DIG. 12,

D8/338, 317, 318; D12/179; 74/551.9, 473.1,

74/473.12; 16/110.1, 421, 430

See application file for complete search history.

FIG. 4 is a front view thereof;

FIG. 5 is a rear view thereof;

FIG. 6 is a top view thereof; and,

FIG. 7 is a bottom view thereof.

(56) **References Cited**

The broken lines shown in the drawings are for illustrative
purposes only and from no part of the claimed design.
